UNITED STATES PATENT OFFICE.

ALBERT G. SLATER, OF VIELE, IOWA.

MATCH-BOX.

No. 855,993.

Specification of Letters Patent.

Patented June 4, 1907.

Application filed September 29, 1906. Serial No. 336,715. (Model.)

To all whom it may concern:

Be it known that I, ALBERT G. SLATER, a citizen of the United States, residing at Viele, in the county of Lee and State of Iowa, have 5 invented new and useful Improvements in Match-Boxes, of which the following is a specification.

This invention relates to match boxes, and 10 one of the principal objects of the same is to provide means for delivering one match at a time to a position to be withdrawn by the user.

Another object of the invention is to provide simple and reliable means for sliding 15 one match at a time out of the box and to prevent matches from accidentally dropping out of the box.

These and other objects may be attained by means of the construction illustrated in 20 the accompanying drawings, in which:—

Figure 1 is a side elevation of a match box made in accordance with my invention. Fig. 2 is a vertical, sectional view on the line 2—2 of Fig. 1. Fig. 3 is a plan view of the box, 25 looking down upon the top thereof. Fig. 4 is a transverse, sectional view on the line 4—4 of Fig. 1. Fig. 5 is a detail, perspective view of the spring and the match ejector mounted to slide thereon.

30 Referring to the accompanying drawing for a more particular description of my invention, the numeral 1 designates a match box which may be conveniently made of comparatively thin sheet metal or other material, 35 said box being substantially oval in cross section and provided with an extension 2 into which a single match may be placed by holding the box in the position to permit the match to roll by gravity from a number with- 40 in the box 1. The projecting portion 2 is provided upon one wall with a slide 3 and a spring 4, formed of a piece of flat spring metal, is riveted at 5 to the extension 2 im- 45 mediately under the slot 3. The spring 4 is curved normally and is provided with an angular upper end 6, said end having a recess 7 therein to permit the match to pass through the same when said spring is in the position to permit the match to be delivered. The 50 end 6 is provided with a notch 8 adapted to engage a projection 9 on the edge of the box adjacent to said notch. A match delivering slide 10 is mounted to slide upon the spring 4 and is provided with a roughened surface 11 55 to engage the match, said slide having a but- 10 button 12 projecting through the slot 3 in the

extended portion of the box. Upon reference to Fig. 2, it will be noted that the slot 3 is formed in a projecting portion 13 of the box and that the match slide 10 is spaced from the button 12 by a reduced neck 14 which serves to hold the match slide against inward and outward movement relatively to the slot 3. A hinged cover 15 is connected to the bottom of the box and provided with a notch 16 to hold the box closed. The opposite end 17 of the box is permanently closed excepting at the point within the top of the extension 2, where the match is delivered.

The operation of my match box may be 70 briefly described as follows: A match having been rolled into the recess a, Fig. 4, between the match slide 10 and the wall of the extension 2, the button 12 is pushed upward carrying the match slide and the match b up- 75 ward and out through the opening 7 in the spring 4. It is to be noted that as the match slide 10 moves upward it straightens out the curve in the spring until it assumes the position shown in dotted lines in Fig. 2, thus 80 drawing the recess 7 into alignment with the match. After the match has been withdrawn from the box, the spring 4 moves to the position shown in full lines in Fig. 2 and the notch 8 engages the projection 9 to hold 85 said spring in this position, thus preventing any of the matches from accidental removal from the box until the slide 10 is again operated. It will be understood, of course, that the slide 10 is returned to its lowermost 90 position after each match has been delivered.

From the foregoing it will be obvious that a match box made in accordance with my invention is of simple construction; will op- 95 erate reliably to deliver one match at a time from the box; can be manufactured at slight cost and cannot readily get out of order in use.

Having thus described my invention, what 100 I claim is:

1. A match box comprising a hollow box or casing for containing matches, an extension formed on the box and provided with a recess adapted to contain a single match, a 105 spring secured in said extension and having its upper end bent to close the outlet to said extension, a match slide mounted to slide upon said spring, and a button on said slide for moving the same upward to carry a 110 match.
2. A match box provided with an exten-

sion, a spring secured in the extended portion, a match deliverer mounted to slide on said spring, and an angular extension on said spring for covering the match outlet.

- 5 3. A match box comprising a hollow casting provided with a slotted extension, a curved spring secured in said extension and provided with an angular upper end which normally covers the outlet for the matches, said upper end being provided with a curved

recess and a notch, said notch adapted to engage a projection on the box to hold the spring in position to close the match opening, and means for delivering a match.

In testimony whereof, I affix my signature ¹⁵ in presence of two witnesses.

ALBERT G. SLATER.
